Primary Examiner — Jae Liang*Assistant Examiner* — Riya Salil Kamat(74) Attorney, Agent, or Firm — Hayes Soloway P.C.(57) CLAIM

The ornamental design for a paddle racket, as shown and described.

DESCRIPTION

FIG. 1 is a front view of a paddle racket showing my new design;

FIG. 2 is a back view thereof;

FIG. 3 is a left view thereof;

FIG. 4 is a right view thereof;

FIG. 5 is a bottom view thereof;

FIG. 6 is a top view thereof;

FIG. 7 is a perspective view of the front, left, and bottom sides thereof; and,

FIG. 8 is a perspective view of the back, left, and top sides thereof.

The broken lines show portions of the paddle racket and form no part thereof.

1 Claim, 8 Drawing Sheets(56)
